UNITED STATES PATENT OFFICE.

PHILIP MUELLER AND ANTON C. SCHUERMANN, OF DECATUR, ILLINOIS, ASSIGNEES
TO ADOLPH MUELLER, TRUSTEE, OF DECATUR, ILLINOIS.

BUBBLER HEAD.

Original application filed November 12, 1919, Serial No. 337,494. Divided and this application filed October 10, 1923. Serial No. 337,712.

To all whom it may concern:

Be it known that PHILIP MUELLER and ANTON C. SCHUERMANN, citizens of the United States, residing at Decatur, in the 5 county of Macon and State of Illinois, have invented new and useful Improvements in Bubbler Heads, of which the following is a specification.

This invention, which is a division of applicants' co-pending application, Serial No. 337,494, filed November 12th, 1919, and which has been made the subject of a separate application under official requirement, relates to sanitary drinking fountains, and 15 more particularly to improvements in the nozzle or bubbler head of such installations.

Primarily, the invention has for its object, the provision of means for effectively permitting the discharge of water to issue 20 from the drinking orifice in a heaped-up form, and with a constant and steady flow so that the danger of the flow of water assuming the force of a jet is eliminated.

By reason of the particular formation of 25 the nozzle or bubbler head, the circulation of water within the nozzle is such that the incoming water will at all times force out the water previously delivered to the head of the nozzle, and thus prevent the stagnation 30 of water within the head.

Additionally, the mouth of the nozzle is so formed as to cause the water to issue therefrom in a globular or spherical form without danger of splashing over the face of 35 the user.

Referring to the drawings, wherein is set forth a preferred embodiment of our invention:

Figure 1 is a vertical sectional view of the 40 upper portion of a drinking fountain and pedestal with our improvement mounted thereon.

Figure 2 is a detailed sectional view of the nozzle or bubbler head.

Figure 3 is a bottom plan view of the bubbler head.

Figure 4 is a bottom plan view of the plate to which the bubbler head is secured.

Figure 5 is a sectional view of the lower 50 edge of the bubbler head showing the undercut groove for effecting engagement with the plate.

Referring to the drawings, wherein like

numerals indicate like parts in the several views, 10 designates a pedestal, which, as is 55 customary in such installations, houses the supply and waste pipes and their associated parts. As the pedestal forms no part of the present invention, the upper portion only is shown. 11 designates a waste pipe, which is 60 preferably traversed by the supply pipe 12. If desired, however, this construction may be varied to permit the supply pipe to enter the waste pipe at an angle thereto. The bowl 13 of the drinking fountain is supported 65 on the pedestal 10, and together with the strainer 14 is secured to the waste connection 15 by the screws 16.

The waste pipe 11 has secured thereto the coupling nut 17, having a flange 18 provided 70 with threaded openings, which receive the set screws 19, the set screws being tightened downwardly onto a plate 20 resting upon the lugs 21 integral with the pedestal 10.

A nipple 22, having an enlarged threaded 75 recess 23 adapted to receive the upper end of the supply pipe 12 extends through a centrally disposed sleeve 24 of the strainer 14. The upper end of the nipple 22 is provided with a reduced shoulder portion 25, which 80 supports the plate 26. The baffle cap 27 has an internally threaded opening 28 which engages the threaded end of the portion 25 of the nipple 22 so as to maintain the plate 26 in position. The side or cylindrical wall of 85 the baffle cap 27 is provided with a plurality of openings or slots 29, through which the water discharges laterally into the nozzle or bubbler head 30.

The plate 26 adjacent its outer periphery 90 has a depending flange 31, and extending laterally from the plate is a plurality of integral lugs 32, four of such lugs being shown in the present instance. The plate 26 has a through aperture 33 to permit drainage from 95 the bubbler head and preferably this aperture is open at all times so as to insure against stagnation of water in the lower part of the head.

The nozzle or bubbler head 30 is preferably 100 circular in cross section and intermediate the ends of the head it is of restricted diameter. The wall of the nozzle is gracefully curved inwardly at its upper end and terminates in a drinking orifice 34 circular in cross section. The outer edge about 105

the opening or orifice 34 is bevelled as at 35 so as to eliminate sharp edges, and assist the drinking bubbler in assuming a globular or spherical form. The open lower end 5 of the nozzle flares outwardly and is provided with an internal circumferential groove 36, below which projects the spaced rib 37, as shown in Figure 3. Vertical slots 38 formed in the bottom of the nozzle 10 30 are equal in number and spaced apart similarly to the lugs 32 on the plate 26 so as to receive the same. The plate 26 is moved inwardly of the nozzle 30 until the lugs 32 lie in the groove 36, whereupon the 15 nozzle is given a partial rotation so that the lugs rest against the rib 37. The groove 36 is then filled with a suitable cementitious material.

As heretofore stated, the nozzle 30 at its 20 central portion is of reduced or restricted diameter, as at 39, and the chamber 40 below this reduced portion flares downwardly and outwardly. The internal walls of the chamber 41 above the restricted portion 39 25 flare upwardly and outwardly and then curve inwardly and slope upwardly until they terminate in the drinking orifice 34. By reason of this construction, the water issues through the slots 29 of the baffle cap 30 into the enlarged chamber 40, and due to the restricted portion 39, the water is conducted into the upper chamber 41 at increased velocity. The water, upon reaching the upper chamber will spread outwardly 35 until it meets the upwardly and inwardly inclined walls of this chamber, which direct the water to flow towards the drinking orifice. Due to the inwardly inclined walls of the chamber 41, the water issues from 40 the drinking orifice in cross currents, and at an angle to the axis of the opening 34 so that the result is that the drinking bubble assumes a globular or spherical form. The water issues from the drinking orifice without violence so that anyone may drink therefrom with ease and comfort.

It is to be understood that our invention is susceptible to various changes and modifications without departing from the spirit

thereof and the scope of the appended 50 claims.

We claim:

1. In combination, a bubbler head having an internal circumferential groove, an interrupted rib below said groove, a supply 55 pipe extending through the lower end of said bubbler head, a plate having a drainage opening mounted on said pipe, and radially projecting lugs on said plate adapted to engage the groove in said bubbler head. 60

2. In combination, a bubbler head having an internal circumferential groove, an interrupted rib below said groove, a supply 65 pipe extending through the lower end of said bubbler head, a plate having a depending flange adjacent its outer periphery, radially extending lugs on said plate adapted to engage the groove on said bubbler head, and means permitting drainage flow through said plate. 70

3. In combination, a bubbler head having an internal circumferential groove, an interrupted rib below said groove, a supply pipe extending through the lower end of said bubbler head, a plate having a drainage opening mounted on said pipe, radially projecting lugs on said plate adapted to engage the groove in said bubbler head, and a baffle 75 cap secured to said pipe having its upper end closed and its side walls provided with 80 outlet openings. 75

4. In combination, a bubbler head having an internal circumferential groove, an interrupted rib below said groove, a supply 85 pipe extending through the lower end of said bubbler head, a plate having a depending flange adjacent its outer periphery, radially extending lugs on said plate adapted to engage the groove on said bubbler head, means permitting drainage flow 90 through said plate, and a baffle cap secured to said pipe having its upper end closed and its side walls provided with outlet openings. 95

In testimony whereof we have hereunto set our hands.

PHILIP MUELLER.

ANTON C. SCHUERMANN.
